[57] CLAIM

The ornamental design for a membrane eye shield, as shown and described.

DESCRIPTION

FIG. 1 is a perspective view of a membrane eye shield showing my new design;

FIG. 2 is a top plan view thereof;

FIG. 3 is a bottom plan view thereof;

FIG. 4 is a front elevational view thereof, the rear elevational view being substantially a mirror image of the front elevational view; and,

FIG. 5 is an end view of the membrane eyeshield as seen from the left side, the end view as seen from the right side being substantially a mirror image thereof.

The broken line showing in FIGS. 1-5 is for illustrative purposes only and forms no part of the claimed design.
